UNITED STATES PATENT OFFICE

CANAAN DE CAZEN, OF MONTREAL, QUEBEC, CANADA

FIREARM AND THE LIKE

Application filed November 10, 1930. Serial No. 494,750.

The present invention relates to improvements in firearms, and the main object of this invention is to provide a two barrel repeating gun, each of said barrels, having a respective firing mechanism, independent from one another. Another object is to provide a gun with a shot gun bore and a rifle bore in order that the user carries one gun only, instead of two.

5 A further object is to provide a gun with two barrels each having an independent firing mechanism, said firing mechanisms being controlled by a single finger-lever, which operates the breech-bolts to close, ready for 10 firing, or extract the fired shell or shells.

This invention principally consists in providing a gun with two barrels, which may be adapted to fire different caliber cartridges or one of said barrels being adapted to fire 15 bullet cartridges and the other shot cartridges. Each of said barrels is respectively provided with a breech-bolt, a cartridge magazine and an independent trigger mechanism. The breech-bolts are suitably connected to one single finger-lever and actuated thereby. The breech-bolts are each provided with a pivoting cam-member which is adapted to become disengaged from the connecting members of the finger-lever, when the 20 breech-bolt is in firing position. After one or both of the breech-bolts have been fired, they automatically engage the finger-lever, which upon opening will actuate said bolt or bolts to extract the fired shell and when closing same will reload the gun.

This particular arrangement will be further fully described as well as other details of construction, such as the barrels which are preferably made of one integral piece of 25 metal, the smaller rifle bore, if the gun has two bores of different calibers, being located below the horizontal plane of the shot bore and preferably at equal center thereto, from one end to the other.

45 In the accompanying drawings:

Fig. 1 is a segmentary side elevation view of a gun according to the present invention, a portion of the side wall of the receiver being broken away to disclose the inner mechanism;

Fig. 2 is a top view of Fig. 1, the top portion being broken away to disclose the breech-bolt mechanism; and

Fig. 3 is an enlarged cross-section view of the barrel unit showing the two bores and their relative position with one another.

Like numerals of reference indicate corresponding parts in each figure.

Referring to the drawings, 1 represents the receiver or casing in which the firing mechanism is lodged, and 2 the butt-stock which is secured to the receiver by the usual butt-stock screw, not shown. In the top of the receiver are provided, preferably, two parallel breech-openings 3 through which the cartridges 4 are inserted and the shells ejected. Below said breech openings 3 are located the magazines 5. As there are two barrels, it has been found preferable to provide two breech openings and two independent magazines, one for each barrel. Below the receiver is suitably pivotally mounted the finger-lever 6, and in the forward end of said receiver is secured the barrel unit 7.

The barrel unit 7 consists preferably of 75 one piece of metal with two longitudinal and parallel bores 8 and 9, respectively. In the accompanying drawings, the bore 8 is for shot cartridges, while the bore 9 which is of smaller diameter, is for rifle cartridges. The 80 outer walls 10 of the bore 8 will therefore be of a larger diameter than the outer walls 11 of the bore 9, and the center of said rifle bore 9 will be in horizontal plane with the center of the shot bore 8, as shown in Fig. 3, of the 85 drawings. Located above the outer wall 11, and integral therewith is provided a longitudinal embossment 12, which extends the full length of the barrel unit 7 and is parallel thereto, and upon said embossment are mounted the front sight 13 and rear sight 14.

In each of the breech-openings 3, is respectively and slidably mounted the breech-bolts 15 and 16, the breech bolt 15 co-operating with the bore 9 and the breech-bolt 16 with the bore 8 of the barrel unit 7. Said breech-bolts are respectively provided with the usual hammer 17 and firing pin 18, around which coils the hammer-spring 19. In the outer side of each of said breech-bolts 15 and 16 is 100

provided a longitudinal slot 20 in which is pivotally mounted at 21, in suitable brackets, the cam lever 22, one end of said lever carrying the cam-member 23 while the other end 5 which may be slightly curved or bent contacts with the outer wall of the tapered shape firing-pin 18. When the firing-pin is in its operative position, that is when it is in firing position, the end of the cam-lever 22 will be 10 pressed inwardly against the tip of the firing-pin by means of the small spiral spring 24, which is located in the side of said breech-bolt adjacent its cam-end. When in this position, the cam-member 23 carried at the other 15 end of the lever 22, will be out of engagement with the end of the lever 25, which normally engages the cam, the action of which will be described hereinafter.

The hammer 17 operating in the breech-bolt is engaged by the hammer-retractor 26, co-operating with the usual trigger 27, and each hammer is controlled by an independent trigger. In the present instance, there are 20 two triggers, one for each hammer.

The finger-lever 6 which is located below the receiver 1, is preferably provided with a cross or enlarged horizontal member 28 and in each end of said cross-member is rigidly secured a curved-lever 25, each terminating 25 in the rounded end 29, respectively engaging the cam-groove 30, which is provided in each of the cam-members 23. By opening the finger-lever, both breech-bolts will be retracted, similarly as in an ordinary rifle, if both barrels have been fired, as both cams 30 will be engaged by their respective curved lever 30, but if only one barrel has been fired and the hammer controlling the other barrel is still in firing position, as disclosed in Fig. 2 35 of the drawings, the end of the curved lever 25 will be out of engagement with the cam-groove 30, and in this instance, only the breech-bolt which has been fired will be retracted to extract the shell and reload the barrel upon closing the finger-lever.

If it is desired to unload the gun, that is to remove the cartridges from the barrels, without firing, when one or both hammers are in firing position, an opening 31, is provided in 50 each side wall of the receiver, adjacent the cam-members 23, and by inserting the thumb or one of the fingers, the said cam-member may be pressed inwardly into engagement with the end 29 of the lever 25, and the finger-lever 55 may be operated to extract the cartridges.

When the cam-member 23 is out of engagement with the lever 25, its rear end 60 preferably abuts against the shoulder 32 provided in the inner wall of the receiver, thus locking from rear movement the breech-bolt, while the adjacent breech-bolt is operated to extract the fired shell. When the lever 25 is actuated in a backward direction 65 when engaged in the cam member 23, it car-

ries back the breech bolt and the shell is extracted. When the lever is actuated in a forward direction to reload, it leaves contact with the cam 23 and continues in its forward course and pushes upon the end of the breech bolt casing until complete closure of the breech bolt is effected. With this structure, the breech bolt is closed without interfering with the cocked firing pin.

It has been explained that each breech-bolt has a magazine chamber 5, and in each of said magazines may be provided a spring 32A that will normally press the cartridges upward into the breech opening or else the magazine may be provided with the usual magazine carrier (not shown) or any other suitable arrangement.

It should be noted that only the principal parts of the rifle mechanism bearing on the present invention have been disclosed in the drawings and herein described, as all the remaining mechanism is well known and may be of the usual type.

It is also well understood that only a preferred form of the invention has been disclosed, and that modifications may be made without departing from the spirit and scope of the following claims for novelty.

What I claim as my invention is:

1. A repeating gun, comprising a receiver 95 having two breech-openings, two barrels mounted in said receiver, a butt-stock secured to said receiver, a breech-bolt slidably mounted in each of said breech openings, a hammer and firing pin mounted in each of said breech-bolts, a trigger and trigger mechanism controlling each of said hammers, a finger lever simultaneously engaging each of said breech-bolts, and means to disengage said breech-bolts from said finger lever when in firing position.

2. A repeating gun comprising two barrels, a breech-bolt for each of said barrels, and a finger-lever actuating each of said breech-bolts independently.

3. A repeating gun comprising two barrels, a breech-bolt for each of said barrels, a finger-lever engaging and actuating each of said breech-bolts, and means to automatically disengage one or both of said breech bolts 111 when said breech bolts are in firing position and automatically engage said finger-lever when in non-firing position.

4. A repeating gun comprising two barrels, a breech-bolt for each of said barrels, a movable cam-member mounted on each of said breech-bolts, a finger-lever engaging said cam-members and means to disengage one or both of said cam-members when said breech-bolts are in firing position.

In testimony whereof I affix my signature.
CANAAN DE CAZEN.
